UNITED STATES PATENT OFFICE.

WALTER B. SCOTT, OF MARBLEHEAD, MASSACHUSETTS.

DESIGN FOR A WIND NOVELTY.

Application filed June 15, 1925. Serial No. 13,785. Term of patent 7 years.

To all whom it may concern:

Be it known that I, WALTER B. SCOTT, a citizen of the United States, residing at Marblehead, in the county of Essex and State of Massachusetts, have invented a new, original, and ornamental Design for Wind Novelty, of which the following is a specification, reference being had to the ac-

companying drawing, forming part thereof.

Figure 1 is a side view of a wind novelty; Figure 2 is a perspective view of a wind novelty, showing my new design.

I claim:

The ornamental design for a wind novelty, as shown.

WALTER B. SCOTT.
